DESIGN.

S. ROGGENBURGER.

CAP.

18,710.

Patented Oct. 30, 1888.

UNITED STATES PATENT OFFICE.

SIGMOND ROGGENBURGER, OF PHILADELPHIA, PENNSYLVANIA.

DESIGN FOR A CAP.

SPECIFICATION forming part of Design No. 18,710, dated October 30, 1888.

Application filed September 8, 1888. Serial No. 284,934. Term of patent 7 years.

To all whom it may concern:

Be it known that I, SIGMOND ROGGENBURGER, a citizen of the United States, residing in the city and county of Philadelphia, State 5 of Pennsylvania, have invented and produced a new and original Design for a Jockey-Cap, of which the following is a specification, reference being had to the accompanying photograph, forming part thereof.

10 The leading features of my design for a knitted hood or cap are a rounded head portion with a peak or visor, neck-flap curved outward from its connection with the head, and ear-coverings curved forward and downward 15 from their connections with the neck-flap and head.

In the photograph, A represents the cap, consisting of the crown 1, neck-flap 2, ear-coverings 3, and a peak or visor, 5. The neck-

flap is curved outwardly in vertical direction, 20 and the ear-coverings curve forward from the places of junction with the neck-flap to the bottom of said coverings, as shown at 4.

Having thus described my invention, what I claim as new, and desire to secure by Letters 25 Patent, is—

A design for a hood or cap having a rounded head portion with a peak, a neck-flap curved outward from its connection with the head portion, and ear-coverings curved downward and 30 forwardly from their connections with the neck-flap and head, all of said parts having the appearance of knitted fabric, as shown and described.

SIGMOND ROGGENBURGER.
